CURLING ROD

Harry Bonat, New York, N. Y., assignor to Samuel Bonat & Bro., New York, N. Y., a copartnership

Application October 24, 1945, Serial No. 624,274

9 Claims. (Cl. 132—42)

1

The invention relates to improvements in curling rods, and more particularly to a novelly constructed curling rod of a kind especially useful for cold permanent waving. In permanent waving of the human hair, and particularly in the practice of that type of permanent waving known as cold permanent waving, the hair on the head is divided into individual tresses and these tresses are wound upon curling rods. Either before or after winding, the tresses of hair are saturated with a permanent hair waving solution which softens the hair or otherwise conditions it so that it will conform to its wound shape. The waving solution is allowed to remain upon the wound tresses of hair for a predetermined period of time and it is subsequently washed off with water or other like neutral solution.

Removal of the waving solution permits the hair to regain its initial structural condition and after it has been removed from the curling rod and dried, the tresses of hair will remain curled.

In practice, it has been found that satisfactory results are best obtained, when using this method of cold permanent waving, when the waving solution and the neutralizing solution are permitted to penetrate to the innermost strands of hair in the wound tress so as to effect complete saturation thereof. In instances where complete saturation of all of the hair in the wound tress is not effected, the finished curl frequently has portions thereof which do not remain curled and as a consequence the finished curl is imperfect and the hair dress as a whole is not uniform.

It is, therefore, an object of the present invention to provide a curling rod useful in permanent waving of the hair which is constructed in a novel manner to facilitate complete penetration of the perment waving and neutralizing solutions throughout the entire body of a hair tress wound upon said curling rod.

Another object of the invention is to provide a curling rod of a kind having a shaped cage-like body terminating at its ends in novel fittings secured thereto in such manner as to retain the cage-like body in its intended shape.

Another object of the present invention is to provide a curling rod of the character referred to which embodies novel structural features enabling the waving and neutralizing solutions to pass freely therethrough and throughout the body of a hair tress wound thereon.

Another object of the present invention is to provide a novelly constructed curling rod which is easy and inexpensive to manufacture, simple to use, and very efficient.

Other and further objects of the present invention will be apparent from the following description and claims and are illustrated in the accompanying drawing which, by way of illustration, shows a preferred embodiment and the

2

principle thereof and which is considered to be the best mode contemplated for applying that principle. Other embodiments of the invention embodying the same or equivalent principle may be used and structural changes may be made as desired by those skilled in the art without departing from the present invention and the purview of the appended claims.

In the drawing:

Fig. 1 is a side elevational view of the curling rod, showing portions of the securing strand broken away.

Fig. 2 is an enlarged longitudinal central sectional view of the curling rod showing an intermediate portion thereof broken away.

Fig. 3 is an end elevational view of the curling rod.

Fig. 4 is a transverse sectional view taken on line 4—4 of Fig. 2.

Fig. 5 is a longitudinal sectional view taken on line 5—5 of Fig. 4.

The curling rod embodying the features of the present invention consists generally of a shaped body portion 11 and end fittings 12. The body portion 11, preferably is fashioned substantially cage-like and it consists of a plurality of circumferentially spaced apart longitudinal bars 13, each of which is curved longitudinally so that, when mounted in the manner illustrated, the medial portion of the cage-like body is contracted as shown. Each of the bars 13 has its end portions bent substantially at right angles to the length thereof to provide radial portions 14, and said end portions are again bent to provide terminal portions 15 extending outwardly endwise substantially parallel to but in a different plane than the main portion of the bar 13.

The end fittings 12 are identical and as best shown in Fig. 2 each preferably is fashioned from round stock shaped to provide two diameters 16 and 17 so as to provide an external annular shoulder 18 midway between its ends. The portion of the fitting 12 having the smaller diameter is bored axially, as at 19, and it has a plurality of circumferentially spaced lips 21 extending normally outwardly longitudinally from its ends. The lips 21 are, as mentioned hereinbefore, circumferentially spaced apart so as to provide spaces 22 therebetween each to receive therethrough the radial end portion 14 of one of the bars 13 when assembled. When the bars 13 are positioned with their radial portions 14 extending between adjacent parts of lips 21, the longitudinally extending terminal portions 15 thereof project into the respective bores 19 and said bars 13 are firmly held in place by the lips 21 which are bent over inwardly towards one another, as best shown in Figs. 2, 4 and 5. This manner of mounting the bars 13 and the end fittings 12 provides a very rigid construction wherein the ter-

5 minal portion 15 of each bar is firmly anchored within the respective fitting 12, and the relative positions of the bars 13 circumferentially are retained by the lips 21 which extend therebetween and prevent said bars from rocking about their anchored terminals.

In use, the free end of a hair tress is held or clamped against the contracted medial portion of the cage-like body 11 of the curling rod preferably by means of a clamp 23 pivotally mounted, as at 24, on one of the bars 13. The curling rod is held at the end fittings 12 and is rotated so as to wind the hair tress about the body thereof. When the hair tress is completely wound about the body 11 the curling rod is then located close to the scalp and the hair tress is secured against unwinding by any suitable means, such as by the use of a strand 25 of resiliently flexible material such as rubber or the like. The securing strand 25 has one end secured detachably to one end fitting 12, preferably by being provided with an aperture 26 adjacent an end of such diameter as to fit snugly over the reduced diameter 17 of the respective end fitting. The other end of the strand 25 likewise has an aperture 27 adjacent thereto which is engaged over the other end fitting 12. Inadvertent displacement of the securing strand 25, when connected to the end fittings in the manner described, is prevented by the resiliency of the strand itself which retains it taut and also by the provision of the shoulder 18 on each fitting which serves to prevent the respective end of the strand 25 from sliding outwardly off of the fitting engaged thereby.

It might be observed at this time that the cage-like structure of the body 11 facilitates thorough penetration and complete saturation of the hair tress because its open construction enables the solution to flow freely throughout the entire bulk of the wound hair tress and through the interior of the curling rod body. Thus, when an excessive amount of solution flows through the uppermost portion of the wound tress it passes freely through the curling rod and into those portions of the hair tress oppositely disposed thereto.

After the curl has been treated with the waving solution and with the neutralizing solution, it may be dried while remaining on the curling rod body 11 and then removed or it may be removed from said curling rod body prior to drying, easily and quickly by dis-engaging the securing strand 25 from either of the end fittings 12 and unwinding.

It should be understood that although the present disclosure teaches a preferred form of construction the number and cross-section of the bars 13 may be other than as shown and that other variations in detail construction may be made without departing from the spirit of the present invention and the scope of the appended claims.

I claim:

1. A curling rod comprising spaced cylindrical end fittings and bars connecting said end fittings to provide a cylindrical cage-like body, said bars having offset end portions embedded in said end fittings, and a clamp pivotally connected to one of said bars.

2. A curling rod comprising spaced cylindrical end fittings each having an axial bore in one end and a plurality of bars connecting said end fittings to provide a cylindrical cage-like body, said bars having end portions extended into said bores, and a clamp pivotally connected to one of said bars.

3. A curling rod comprising spaced cylindrical end fittings each having an axial bore in one end and a plurality of circumferentially spaced lips on said end, and a plurality of bars connecting said end fittings to provide a cylindrical cage-like body, said bars having end portions disposed between said lips and extended into said bores, and a clamp pivotally connected to one of said bars.

4. A curling rod comprising spaced end fittings each having a bore in an end, outwardly extending circumferentially spaced lips surrounding said bores, and a plurality of circumferentially spaced bars extending between said end fittings, said bars having radially disposed portions to lie between said lips and longitudinally extending terminal portions to extend into said recesses, said lips being deformable to overlie the radially disposed end portions of said bars to secure the bars to said end fittings, and a clamp pivotally connected to one of said bars.

5. A curling rod comprising an elongated medially contracted cage-like body formed of end fittings and a plurality of bowed bars, each of said bars having longitudinally extending offset terminal portions secured in said end fittings.

6. A curling rod comprising a medially contracted cage-like body formed of spaced end fittings, each having an axial bore and a plurality of bowed bars connecting said end fittings, each of said bars having longitudinally extending offset terminal portions secured in said bores.

7. A curling rod comprising a medially contracted cage-like body formed of spaced end fittings, each having an axial bore and a plurality of circumferentially spaced lips adjacent thereto, and a plurality of bowed bars connecting said end fittings, each of said bars having longitudinally extending offset terminal portions disposed between said lips and extending into said bores.

8. A curling rod comprising a medially contracted cage-like body formed of a fitting at each end of said body, and circumferentially spaced bowed bars connecting said fittings, each of said bars having longitudinally extending offset terminal portions in substantial abutment, each of said end fittings having a recess to receive said offset terminal portions and having means for securing the same in said recess.

9. A curling rod comprising a cage-like body formed of a substantially cylindrical fitting at each end thereof, and circumferentially spaced bars connecting said fittings, each of said fittings having an axial bore and a plurality of circumferentially spaced lips adjacent thereto, said bars having terminal portions disposed between the said lips and extending into said bore, said lips being deformable inwardly to secure said bars to said fittings.
